US0D1011573S

(12) **United States Design Patent** (10) **Patent No.:** **US D1,011,573 S**
(45) **Date of Patent:** **** Jan. 16, 2024**

(54) **LIGHTING APPARATUS**

(71) Applicant: **MILWAUKEE ELECTRIC TOOL CORPORATION**, Brookfield, WI (US)

(72) Inventors: **Benjamin D. Gall**, Milwaukee, WI (US); **Matthew D. Strommen**, Greendale, WI (US); **Kevin R. Kirk**, Minnetonka, MN (US)

(73) Assignee: **MILWAUKEE ELECTRIC TOOL CORPORATION**, Brookfield, WI (US)

(**) Term: **15 Years**

(21) Appl. No.: **29/774,692**

(22) Filed: **Mar. 18, 2021**

(51) **LOC (14) Cl.** **26-02**

(52) **U.S. Cl.** **USPC** **D26/37**

(57) **CLAIM**

We claim the ornamental design for a lighting apparatus, as shown and described.

DESCRIPTION

FIG. 1 is a perspective view of a lighting apparatus embodying the invention.

FIG. 2 is a top view of the lighting apparatus of FIG. 1.

FIG. 3 is a bottom view of the lighting apparatus of FIG. 1.

FIG. 4 is a first side view of the lighting apparatus of FIG. 1.

FIG. 5 is a second side view of the lighting apparatus of FIG. 1.

FIG. 6 is a third side view of the lighting apparatus of FIG. 1; and,

FIG. 7 is a fourth side view of the lighting apparatus of FIG. 1.

Portions of the lighting apparatus shown in broken lines form no part of the claimed design.

1 Claim, 7 Drawing Sheets
